UNITED STATES PATENT OFFICE.

WILHELM HIRSCHKIND, OF ANTIOCH, CALIFORNIA, ASSIGNOR TO GREAT WESTERN ELECTRO-CHEMICAL COMPANY, OF SAN FRANCISCO, CALIFORNIA, A CORPORATION OF CALIFORNIA.

PROCESS FOR MANUFACTURE OF DIXANTHOGEN.

No Drawing.

Application filed May 24, 1926. Serial No. 111,379.

This invention relates to the production of di-xanthogen, a compound produced from alkali metal xanthate by the use of various oxidizing agents, such as iodine 5 chlorine, or cupric salts. Electrolytic oxidation may also be used for the production of the material. The latter method has advantages over the others for the reason that no deleterious chemicals are used in 10 the process and therefore no impurities are found in the product which necessitate additional treatment for their removal.

I have also discovered that di-xanthogen can be produced by an electrolytic oxidation process with only alcohol and carbon bisulphide as the raw materials.

Alkali metal xanthate, as a commercial product, is the result of a reaction between alcohol, carbon bisulphide and an alkali 20 metal hydroxide, a solution thereof in water containing none of these compounds in a free state. Dixanthogen contains no alkali metal but otherwise the identical constituents of alkali metal xanthate.

25 When an aqueous solution of alkali metal xanthate is electrolyzed, the alkali metal is split off and reacts with the water present to form an alkali metal hydroxide, with the result that as the electrolysis proceeds, the 30 concentration of the alkali metal xanthate becomes lower while the concentration of the alkali metal hydroxide rises, the di-xanthogen formed dropping out of the solution as an oily material heavier than said 35 solution.

In practice the electrolysis is carried to an economic point of concentration, both 40 ways, fixed by local conditions such as power, cost and so forth, after which the alkali metal xanthate content is again brought to the original percentage by the 45 addition to the solution in proper quantity of the other two constituents of the alkali metal xanthate, that is alcohol and carbon bisulphide, the alkali metal hydroxide being 50 present in the spent solution. The reactions are cyclic in that at one stage the alkali metal hydroxide reacts with alcohol and carbon bisulphide to produce alkali metal 55 xanthate, after which the electrolysis produces the dixanthogen and alkali metal hydroxide to be again followed by the production of more alkali metal xanthate, the only

fresh material required being alcohol and carbon bisulphide. 55

The process is regeneratively carried out as follows:

Ordinarily the process may be started with a solution of alkali metal xanthate containing approximately 40% of alkali 60 metal xanthate in water with substantially no free alkali metal hydroxide. This solution is then electrolyzed at about three volts with suitable electrodes of lead or platinum, until approximately 25 to 30% of the alkali 65 metal xanthate present has been converted into dixanthogen, which action at the same time liberates an equivalent amount of the caustic alkali in the solution. The apparatus may be arranged for the electrolytic 70 cell to operate continuously or to operate intermittently, as may be desired, but in any event, when the concentration of the caustic alkali in the solution has reached the desired point, alcohol and carbon bisulphide are added to the solution and the 75 solution is allowed to stand with sufficient agitation until the reaction has been completed to bring the quantity of alkali metal xanthate up to the amount originally present 80 in the solution. The solution may then be returned to the electrolytic cell and the cycle repeated.

The dixanthogen is a heavy, oily liquid and when produced will separate from the 85 solution and may be drawn out of the bottom of the electrolytic cell into suitable containers from time to time. The dixanthogen crystallizes in the containers, its melting point being about twenty-eight degrees centigrade. The limit ordinarily set 90 for the electrolysis is 20 to 30% of the alkali metal xanthate originally present in the solution, but this limit may be changed to give the most effective results under 95 given conditions.

Having thus described my invention, what I desire to secure by Letters Patent of the United States is as follows, but modifications may be made in carrying out the invention and in the above particularly described form thereof, within the purview of the annexed claims.

1. A method of producing dixanthogen which consists in the electrolysis of a solution containing alkali metal xanthate until 105

a portion of the xanthate present has been converted into dixanthogen, adding alcohol and carbon bisulphide to the solution causing it to react until substantially all of the free alkali has been absorbed, and then repeating the electrolysis.

2. A method of producing dixanthogen by electrolysis, which consists of electrolyzing an alkali metal xanthate solution until a given amount of free alkali is present, discontinuing the electrolysis, adding alcohol and carbon bisulphide and causing them to react with the free alkali to produce a substantial quantity of alkali metal xanthate and thereafter repeating the electrolysis.

3. A method of producing dixanthogen by the electrolysis of alkali metal xanthate solutions of suitable strength which consists in electrolyzing a suitable solution containing about 40% alkali metal xanthate until a given amount of the alkali metal xanthate has been converted into dixanthogen, discontinuing the electrolysis, adding alcohol and carbon bisulphide to the solution in sufficient quantity to react with the free caustic present causing the reaction thereof to produce alkali metal xanthate, and thereafter again electrolyzing the solution to produce repeated quantities of the dixanthogen.

4. The method of producing dixanthogen which comprises the oxidation of alkali metal xanthate in aqueous solution followed by the addition to said solution of alcohol and carbon bisulphide, from which more alkali metal xanthate will be produced for the cyclic production of more dixanthogen.

5. The method of producing dixanthogen

which comprises the oxidation of alkali metal xanthate in aqueous solution with the corresponding production of alkali metal hydroxide followed by the addition of the necessary constituents to said solution to produce more alkali metal xanthate.

6. The method of producing dixanthogen which comprises the oxidation of alkali metal xanthate in aqueous solution electrolyzing the said solution for the production of dixanthogen, thereafter adding alcohol and carbon bisulphide to produce more alkali metal xanthate, and thereafter again electrolyzing the solution for the production of additional quantities of the dixanthogen.

7. The method of producing dixanthogen which comprises electrolyzing alkali metal xanthate, thereafter adding the necessary constituents to produce additional alkali metal xanthate, followed by an additional production of dixanthogen by electrolysis.

8. The method of producing dixanthogen which comprises electrolyzing an aqueous solution of alkali metal xanthate to produce dixanthogen and free alkali metal hydroxide in the solution, thereafter adding alcohol and carbon bisulphide, agitating the solution until the alcohol, carbon bisulphide and alkali metal hydroxide have reacted to produce alkali metal xanthate at substantially the original percentage, and thereupon again electrolyzing the solution for the production of a further quantity of dixanthogen and free alkali metal hydroxide in solution.

In testimony whereof I have hereunto set my hand this 11th day of May A. D. 1826.

WILHELM HIRSCHKIND.
